DESIGN FOR A SEWING MACHINE OR SIMILAR ARTICLE

Malcolm S. Park, Mount Kisco, N. Y., assignor to
The Singer Manufacturing Company, Eliza-
beth, N. J., a corporation of New Jersey

Application April 11, 1941, Serial No. 100,321

Term of patent 14 years

To all whom it may concern:

Be it known that I, Malcolm S. Park, a citizen
of the United States, residing at Mount Kisco,
New York, have invented a new, original, and
ornamental Design for a Sewing Machine or
Similar Article, of which the following is a speci-
fication, reference being had to the accompany-
ing drawings, forming a part thereof.

Fig. 1 is a front elevational view slightly in
perspective of a sewing machine showing my new
design.

Fig. 2 is a rear perspective view of the same.
Fig. 3 is a left side elevational view slightly in
perspective of the same.

Fig. 4 is a right side elevational view of the
same.

Fig. 5 is a top plan view of the same.

I claim:

The ornamental design for a sewing machine
or similar article, as shown.

MALCOLM S. PARK.
